UNITED STATES PATENT OFFICE

2,425,940

MULTIPLE NOZZLE SELF-PROPELLED
SPRAYER

Neal Jerome Iverson, Mobile, Ala.

Application February 12, 1945, Serial No. 577,449

5 Claims. (Cl. 91—45)

1

The device forming the subject matter of this application is adapted to be employed for applying paint, by air pressure, to the hull of a ship.

Functionally considered, the objects of the invention are to avoid the wasting of paint or the like through loss resulting from wind, to save time and labor in the application of a coating, to eliminate health hazards, and to secure a uniform coating.

The invention aims to provide a carriage of novel form and means for mounting it on the hull of a ship to travel therealong, a rack being suspended from the carriage, the rack carrying the instrumentality whereby the paint is applied immediately. The invention aims, further, to provide novel means for keeping the rack in the proper relation to the hull of the ship, and for controlling the passage of air and paint to the applying nozzles.

A mechanic who abides by what is claimed, may make such changes as his skill may direct, without departing from the spirit of the invention.

In the accompanying drawings:

Figure 1 shows, in front elevation, a device constructed in accordance with the invention;

Figure 2 is a top plan;

Figure 3 is a vertical longitudinal section;

Figure 4 is a section taken approximately on the line 4—4 of Figure 1;

Figure 5 is a section taken approximately on the line 5—5 of Figure 1;

Figure 6 is a section taken on the line 6—6 of Figure 1.

Figure 7 is a vertical sectional view showing part of the adjusting means for the suspended frame;

Figure 8 is an elevation showing the means for operating certain of the valves.

In carrying out the invention, there is provided a substantially horizontal track 1, in the form of a trough, the rear wall of the trough being supplied with suspension hooks 2, carrying set screws 3, the hooks and the screws constituting means whereby the track 1 may be mounted on the bulwarks of a vessel, the hull H of which is to be painted.

A carriage C is mounted to move along the track 1. The carriage C includes a housing 4, in the form of an inverted trough. From the lower edge of the forward wall of the housing 4, a horizontal platform 5 projects. The platform 5 is sustained by brackets 6, which connect it with the forward wall of the trough or housing 4.

Axles 7 and 8 are mounted in the housing 4, near the ends thereof. The axle 7 carries a

2

wheel 9. A wheel 10 is secured to the axle 8. The wheels 9 and 10 are adapted to roll along the track 1.

The wheel 9 is an idle wheel, meaning thereby that no power is applied to it. The wheel 9 is adapted to be engaged by brake mechanism 11, mounted on the endmost of the brackets 6. The brake mechanism 11 may be of any desired construction, and is so located that an operator, 10 standing on the platform 5, may actuate it.

The wheel 10 is power driven, since the axle 8 which carries it is connected by reduction gearing 12, of any desired construction, with a motor 14, mounted on the platform 5. The prime mover 14 may be an electrical motor, but, in any event, it is reversible.

A frame F is disposed below the platform 5. The frame F is V-shaped in cross section as Figures 6, 4 and 5 show. The frame F embodies vertical side posts 15 and a vertical intermediate post 16, connected at their upper ends by top rail 17, and at their lower ends by a bottom rail 18. As Figure 4 discloses, the rails 17 and 18 are V-shaped in plan.

25 The posts 15 and 16 have projections 19, in which rungs 20 are secured. The rungs 20 form parts of ladders, whereby an operator may ascend to the platform 5. Wind shields 21 extend between the side posts 15 and the intermediate post 16, and prevent the paint from being blown about, as it is applied by an instrumentality to be set forth hereinafter. The wind shields 21 are detachable.

Depending guides 22 are carried by the lower 35 rail 18, and in them, slide rods 23 are mounted for horizontal adjustment. Anti-friction members 24 are mounted on the outer ends of the slide rods 23 and, preferably, are wheels mounted to rotate about vertical axes. The wheels 24 are 40 adapted to bear against the hull H of a ship, to space the frame F from the hull, and to do so without unnecessary friction, the throwing of an unnecessary load on the propulsion motor 14 thereby being avoided.

45 In order to prevent the frame F from having a side-swing, downwardly and forwardly extended braces 35 are pivoted at 36 to ears 37 on the intermediate post 16, the braces having sliding adjustment in guides 38 on the platform 5, set 50 screws 39, Fig. 1, being threaded into the guides, and being adapted to engage the braces, to vary their effective lengths.

The frame F is suspended pivotally from the carriage C, for swinging adjustment toward and 55 away from the hull H which is to be painted.

With that end in view, the apex of the upper end of the frame F is connected by a ball socket joint 139 or the like with the forward portion of the platform 5, as shown in Figure 3. A cross bar 40 (Figure 4) connects opposing portions of the top rail 17 of the frame F. On the platform 5 (Figure 7) are mounted brackets 41, wherein nuts 42 are pivoted. Hand screws 43 are threaded through the nuts 42 and are connected by ball and socket joints 44 with the end portions of the cross bar 40.

Conduits 45 and 46 extend along the platform 5 and downwardly along the vertical, forward angle of the frame F, the conduits including flexible upper portions 47, which permit swinging adjustment of the frame F toward and away from the hull H by means of the hand screws 43. One of the conduits 45-46 is a compressed air conduit, and the other is a paint conduit. The conduits 45 and 46 are connected to the forward portion of the frame F by brackets 48 as shown in Figure 3.

Hand valves 49 are interposed in the upper portions of the conduits 45-46, above the platform 5, and there are hand valves 50 in the lower portions of the conduits. Paint and compressed air, therefore, may be fed upwardly or downwardly through the conduits, at the will of an operator, and as convenience may require.

A plurality of vertically spaced pairs of valves 51 are in communication with the conduits 45 and 46, the valves of each pair being connected at 52 with a nozzle 53, there being a vertical line of nozzles discharging toward the hull H of the ship. The valves 51 are opened and closed by crank arms 54, detachably connected by studs 55 and cotter pins 56, or in any other appropriate way, with the side arms of an inverted, U-shaped operating member 57, to the upper end of which is secured a handle 58 mounted at 59 for reciprocation on the upper portions of the frame F, the platform 5 having an opening through which the handle passes in order that the valves 51 may be opened and closed conveniently from above the platform 5.

In practical operation, swinging adjustment of the frame F toward and away from the hull H of the ship may be brought about by manipulating the hand screws 43 of Figure 3, the frame pivoting on the ball and socket joint shown at 139. The frame F is held in any position to which it may have been adjusted, as before said, through the instrumentality of the braces 35 of Figure 1.

The carriage C is caused to move along the track 1 by a train of parts including the motor 14, the reduction gearing 12, the axle 8 and the wheel 10.

By way of the handle 58 and the operating member 57, the valves 51 may be opened. As to the conduits 45 and 46, they deliver paint and compressed air to the valves 51, and from the valves the paint and the compressed air flow through the connections 52 to the nozzles 53. Since there is a vertical line of nozzles, extending throughout practically the entire height of the frame F, a wide section of the hull H will be painted, as the carriage C moves along the track 1, the wheels 24 being in contact with the hull of the vessel. The movement of the carriage C may be stopped by cutting off the motor 14, the brake mechanism 11 being applied. Since the motor 14 is a reversing motor, the carriage C may be moved in opposite directions along the track 1.

It may be that the operator does not desire to have all of the vertically spaced nozzles 53 in operation at the same time. Under such circumstances, he may remove the cotter pins of Figure 5 8 from the studs 55 on such of the arms 54 as is desired, the corresponding pairs of valves becoming inoperative and remaining in a closed position, the operating member 57 and its handle 58 constituting means for opening and closing the other valves 51.

As shown best in Figure 6, the posts 15 of the frame F may be connected, wherever necessary, by one or more tie-rods 15', to aid in avoiding spreading.

15 What is claimed is:

1. In a machine for applying a coating, a track, means for mounting the track in an elevated position on an object to be coated, a carriage movable along the track, a frame depending from the carriage, an applying means mounted on the carriage, anti-friction members engageable with the object to be coated, and means for mounting the anti-friction members on the carriage for adjustment toward and away from the object to be coated.

2. In a machine for applying a coating, a track, means for mounting the track in elevated position on an object to be coated, a carriage movable along the track, a frame depending from the carriage, an applying means mounted on the frame, anti-friction members engageable with the object to be coated, means for mounting the anti-friction members on the lower portion of the frame for adjustment toward and away from the object to be coated, and braces of adjustably variable lengths, having their adjacent ends mounted on the frame and their remote ends assembled with the frame.

3. In a machine for applying a coating, a track, means for mounting the track in a substantially horizontal position upon an object to be coated, a carriage movable along the track, a frame depending from the carriage, and applying devices mounted on the frame, the frame comprising rails and connections between the rails, the connections being offset from the rails and being spaced from each other vertically at such distances as to constitute an effective ladder for ascent to the carriage.

4. In a coating machine, a carriage, means for mounting the carriage for substantially horizontal movement along an object to be coated, a frame depending from the carriage, superposed nozzles on the frame, a conduit discharging into the nozzles, valves individual to the nozzles and controlling the flow from the conduit into the nozzles, crank arms forming parts of the valves, an operating member extended upwardly above the carriage, and connections between the operating member and the crank arms, the connections being readily releasable, whereby any nozzle will remain closed when the operating member is actuated, to open other nozzles.

5. In a machine for applying a coating to an object, a substantially horizontal track, means for mounting the track in an elevated position on an object to be coated, a carriage, means for mounting the carriage on the track for movement therealong, a frame, means for suspending the frame from the carriage, an applying mechanism mounted on the frame, said applying mechanism comprising a plurality of nozzles mounted on the frame in operatively spaced relation, conduits supplying coating material and air pressure to each nozzle, the conduits being mounted on

the carriage, the conduits being opened at their upper and lower ends whereby air pressure and coating material may be supplied from a point on the carriage, or from a point below the frame, valves on the upper portions of the conduits, and valves on the lower portions of the conduits, said valves being under the control of an operator, to permit air pressure and coating material to move either upwardly or downwardly in the conduits at the will of an operator.
